UNITED STATES PATENT OFFICE.

JAMES J. BOYLE, OF NEW YORK, N. Y., ASSIGNOR OF ONE-HALF TO DANIEL P. BOYLE,
OF NEW YORK, N. Y.

PENHOLDER.

1,371,292.

Specification of Letters Patent. Patented Mar. 15, 1921.

Application filed November 17, 1919. Serial No. 338,466.

To all whom it may concern:

Be it known that I, JAMES J. BOYLE, a citizen of the United States, and a resident of the borough and county of Bronx, in the 5 city and State of New York, have invented a new and useful Penholder, of which the following is a specification.

The object of this invention is provide an 10 ejecting pen-holder, which shall be efficient for its particular purpose, and as a holder, which shall be economical for manufacture, and therefore meet an essential practical requirement, namely low selling price, and which shall be acceptable to purchasers as 15 involving no departure from the form and feel of ordinary pen-holders. To this end the invention may be said to consist in the novel construction and combinations herein described and illustrated in the preferred 20 embodiment, and more particularly pointed out in the claim.

In the accompanying drawings forming a part hereof:

Figure 1 is a perspective view of a pen- 25 holder embodying the invention, in the act of ejecting a pen;

Fig. 2 is an enlarged longitudinal section through the forward part of the penholder, in the condition of Fig. 1;

Fig. 3 is a longitudinal section, with parts 30 broken away and in elevation, showing the normal condition, with a pen in place;

Fig. 4 is an elevation of the forward part 35 of the shaft of the penholder with a stem and filler integral therewith;

Fig. 5 is a front end elevation without the pen;

Fig. 6 is a cross-section on the line 6—6 of Fig. 3;

Fig. 7 is a cross-section on the line 7—7 40 of Fig. 3; and

Fig. 8 is a side elevation of the metallic grip tube.

Figs. 1 to 7 will first be described. 45 The shaft 1 of the penholder, of wood or other suitable material, though preferably of wood, is provided at the front with a reduced cylindrical portion 2 forming the stem of a filler 3, between which and the 50 grip member the pen is inserted. The filler proper 3, in this construction, is of wood, or of the same material as the body of the penholder, with which it is integral, and is made a little larger than the stem 2, 55 though not as large as the forward portion

of the shaft, so as to provide a stop shoulder 4. In the sides of the filler are longitudinal grooves 5, extending all the way to the front, where their ends are open.

The grip part of the penholder prefer- 60 ably comprises a metal tube or sleeve 6 and a conventionally shaped grip 7 of rubber or other material held on the tube by out-turned flanges 8 at the ends. The tube is of somewhat larger internal diameter than 65 the filler 3, so as to afford a narrow space in which the pen can be placed and frictionally held. V-projections or indentations 9 are struck in from the tube intermediate its 70 ends, in positions to enter and slide in the grooves 5. These projections constitute a simple and advantageous embodiment of positive ejecting means operated by the forwardly movable grip member. The grooves and projections are sufficient in number, that 75 is to say sufficiently closely spaced in the circumferential direction, to insure that one of the projections will be behind the pen in any position which it may occupy. Four 80 projections are shown, though I do not necessarily limit myself to this precise number.

Toward the rear of the tube in advance of the rear flange 8, a circumferential rib 10 is pressed in to constitute a stop element 85 co-operative with the other stop element formed by the shoulder 4. The relative positions of the stop and ejector are such that when the grip member is at its limit of forward movement the ejector projections 9 are at the front end of the filler, or substan- 90 tially so.

The rib 10 bearing upon the stem 2, and the projections 9 bearing in the grooves 5, prevent any undue looseness, and the fit if desired may be frictional, though the opera- 95 tion is easier if the grip member slides freely on the stem and filler in the absence of the pen. The clearance between the grip tube and filler is such that the pen requires to be pushed in forcibly, and when in place 100 holds the grip tightly against undesired movement.

To remove the pen, the shaft of the penholder is held in one hand and the grip 105 grasped in the other and pushed forward against the frictional resistance. In so doing, the ejector projections 9 are carried forward in the grooves 5, and one or more of them positively advances the pen until it finally falls or is shot out as shown in 110

Fig. 1. There is no possibility of the projections failing to catch the nib, or of the nib lying passively or becoming wedged between the relatively moving parts. The grip is then slipped back to normal position, and a fresh pen put in, whereby the grip is held firmly as just explained.

What I claim as new is:

A pen-holder having a shaft and a filler, 10 with a reduced stem between the filler and shaft affording a stop shoulder, the shaft,

filler and stem being integral and the filler having a plurality of longitudinal grooves, a grip-tube slidable on the filler and stem, with a circumferential nib-socket between 15 it and the filler, said tube being formed with a stop to bear on the neck and coöperate with said stop shoulder, and with a plurality of pressed-in ejector projections disposed around the circuit to operate in said grooves 20 and eject the nib in any position.

JAMES J. BOYLE.
